UNITED STATES PATENT OFFICE.

HENRY J. HEIDER, OF CARROLL, IOWA, ASSIGNOR TO HEIDER MFG. COMPANY, OF CARROLL, IOWA, A CORPORATION.

AXLE-FASTENING.

1,292,771.

Specification of Letters Patent. Patented Jan. 28, 1919.

Application filed May 13, 1918. Serial No. 234,236.

To all whom it may concern:

Be it known that I, HENRY J. HEIDER, a citizen of the United States, residing at Carroll, in the county of Carroll and State 5 of Iowa, have invented a new and useful Axle-Fastening, of which the following is a specification.

This invention relates to axle fastenings, particularly to that class thereof which 10 unites the bolster of a wagon with the axle.

The general object of this invention is to make a fastening clip suitable for use in toy or children's wagons.

Other objects of this invention are to 15 provide a fastening which holds the two wagon parts together securely, which is easily applied, which is simple in manufacture, and which also serves as an end bearing for the wheel to butt against.

20 The accompanying drawing illustrates one practical embodiment of my invention, but I wish it to be understood that I may depart from the illustrated construction in minor details, so long as I keep within the scope of 25 the appended claim.

In the drawing—

Figure 1 is a vertical elevation of my fastening device in place;

Fig. 2 is an enlarged fragmentary vertical 30 longitudinal section to show more clearly the application of the present invention;

Fig. 3 is an enlarged vertical transverse section on the line 3—3 of Fig. 1, looking in the direction indicated;

35 Fig. 4 is an end elevation of the clip plate or block; and

Fig. 5 is a perspective view of the same.

The numeral 10 designates the sand-board or bolster of a wagon such as is commonly 40 called "a coaster." This bolster is united to axle 11 by an eye-bolt 12 whose eye 14 surrounds the axle, and by a clip plate or block 15 which co-operates with the bolt to effect a strong union of the parts. The bolster, 45 axle and eyebolt are of ordinary construction and need no further description.

Clip plate or block 15 is preferably cast iron and is so formed as to resemble the letter L. It consists of two parts, an axle- 50 supporting and hub-bearing member 16, and a bolster-engaging portion 17 extending at right angles thereto. The member 16 is provided with a centrally located bore or hole

18, whose diameter is sufficient to freely admit the axle 11 therein. The bolster engaging portion 17 is provided on its underside with a groove 19 of radius equal to the hole and in alinement therewith. Hence, when the clip plate or block 15, is slipped over the axle, groove 19 rests on the axle; and upon 55 clamping the bolster and axle together, the groove offers a large frictional surface to restrain movement of the axle.

Companion grooves 20 are provided on each side of groove 19. These grooves save 60 metal and hence decrease the weight of the clip plate, but do not affect its strength.

The upper face 24 of member 17 is grooved or recessed to provide marginal flanges on three sides, which flanges enable 70 the clip plate to fit about the underside and end of the bolster. These flanges are of course so spaced that the bolster is engaged freely. The two side flanges 23 taper from the end flange 22 so as to nearly merge with 75 the upper face 24 of the portion 17. Face 24 thus forms a seat for the bolster when it is clamped to the axle. As 25 indicates, the inner face of member 16 may be cut away or reduced to save weight and metal. 80

The function of the invention is apparent from the drawing. The eyebolts force the bolster ends with great force into the seat 24 of the clip plate, whereupon the groove 19 is pressed against the axle so firmly that 85 all movement, both translatory and rotary, is eliminated. The outer face, 16', of the axle supporting member 16 provides an end thrust bearing for the wagon wheel and takes the place of the usual washer. It is 90 made smooth and extends uprightly.

In practice, the eyebolts and axle are partly assembled and the clip plate or block slipped on over the end of the axle, whereupon by tightening the eyebolt, a tension is 95 put on the axle so as to hold it firmly. In this way, there is combined the strength of the wood with the axle.

It is obvious that minor changes may be made in the structure described. Thus, if a 100 square axle is employed, the eyebolt would have a rectangular eye, and groove 19 would be rectangular rather than round.

What is claimed is—

The combination with an axle and a bolster, an eye bolt embracing the axle and se- 105

cured to the bolster, and a block interposed between the axle and the bolster at one side of the eyebolt, said block having an opening for the passage of the axle, and a seat 5 with flanged walls for the reception of the end of the bolster, the outer face of the block being upright and smooth and forming a bearing for the wheel to abut against.

Copies of this patent may be obtained for five cents each, by addressing the "Commissioner of Patents, Washington, D. C."

In testimony that I claim the foregoing as my own, I have hereto affixed my signature 10 in the presence of two witnesses.

HENRY J. HEIDER.
